EVAPORATOR, ESPECIALLY FOR HIGH
PRESSURE STEAM

Ernst Koenemann and Karl Gensch, Berlin,
Germany, assignors to Gesellschaft für Druck-
transformatoren (Koenemann-Transfor-
matoren) G. m. b. H., Berlin, Germany, a corpo-
ration of Germany

Application January 4, 1932, Serial No. 584,736
In Germany January 6, 1931

9 Claims. (Cl. 122—32)

This invention relates to an evaporator, especially for the generation of high pressure steam, heated by means of a liquid medium having a high boiling point, as for instance a fused salt-like chloride of zinc ammoniacate, and has as its main object a particular model of such an evaporator in which water and steam are prevented from penetrating into the heating medium through leakages at the points where the water tubes are joined to the collecting chambers by a rolling or welding process. Furthermore it is possible by our invention, in case of leakage at any of the joints between the water tubes and the heating jacket containing the heating fluid, to easily perceive which joint is defective and to calk it without difficulty. At the same time it is provided that the different degrees of expansion and contraction of the various members of the evaporator do not cause detrimental stresses in the material. Further details of the invention are hereinafter described and illustrated in the attached drawings in which

Figs. 1 and 2 show diagrammatically one illustrative embodiment of the invention, Fig. 1 being a longitudinal section through the evaporator, the upper part of Fig. 2 a plan seen from above, and the lower part of Fig. 2 a section at the line II—II of Fig. 1. Figs. 3 and 4 show a second embodiment of the invention, Fig. 3 being a side view of a part of the evaporator, and Fig. 4 a section at the line IV—IV, of Fig. 3. Figs. 5, 6, 7 and 8 illustrate a third embodiment of the invention, in which Fig. 5 is a side view of the evaporator, Fig. 6 a view from above, and Fig. 7 is a fractional section at the line VII—VII of Fig. 6, and Fig. 8 is a fractional section at the line VIII—VIII of Fig. 5. Figs. 7 and 8 are drawn at a larger scale than Figs. 5 and 6.

The evaporator consists of the following main parts:

The water tubes 1, the collecting chambers 2 and 3 into which the water tubes are inserted, and the heating jacket encasing the water tubes along the greater portion of their entire length. In the model illustrated by Figs. 1 and 2 the water tubes are arranged as two concentric circles. The collecting chambers 2 and 3 are small vertical drums of comparatively small dimensions arranged in the centre of the circle. The upper and lower ends of the water tubes are curved inward at their ends and are at point 6 fixed to the drums by a rolling or welding process. The heating jacket is a double wall cylinder consisting of the outer wall 4, the inner wall 7 and the

annular top and bottom plates 8 and 9. At A the cylinder has a longitudinal slot and therefore the outer and inner casings 4 and 7 are there connected with each other by casing plates 10 and 11.

The water tubes are inserted between the walls 4 and 7 of the jacket and perforate the top and bottom plates 8 and 9 at the points marked 12, where they leave the heating jacket. At the perforating points 12 the water tubes are welded to the jacket, i. e. in any usual or suitable way as by electric or flame welding or by rolling or expanding the metal to form a rolled, expanded, or calked joint, or a stuffing box is inserted at each of these points. On the outer wall 4 are the flanged sockets 13 and 14 through which the heating fluid is supplied and discharged.

This fluid is heated in a separate vessel and continually kept circulating from the vessel to the evaporator and back by means of a pump. The heating medium enters into the heating jacket through one of the sockets, flows along the water tubes and after having delivered heat to them is discharged from the heating jacket and returns to the heating vessel. Heating vessel, pump and the pipe-lines connecting the heating vessel and the heating jacket are not illustrated in the drawings.

The heat delivered by the heating fluid causes the water in the water tubes to evaporate. The mixture of steam and water resulting therefrom flows into drum 2 where the main part of the water carried along is collected and flows through the downcomer 5 to the lower drum 3 from which it is supplied to the various water tubes. The steam is discharged at the socket piece 15, subject, if necessary, to superheating in a special device and then supplied to a turbine or used for any other purpose. The necessary feed-water is supplied to the evaporator through the socket piece 16.

If guide-plates are arranged in the interior of the heating jacket to direct the flow of the heating liquid in such a manner that first of all only a part of the water tubes are heated by the hot fluid delivered by the heating vessel, and the remaining tubes are heated later on, then, owing to the difference in temperature between heating liquid and water being greater at the inlet than at the outlet, the quantity of steam produced in the first-heated tubes is very much higher than that produced in the rest, which is only very small. One could therefore omit the downcomers because the water tubes which are only mod-

erately heated would serve as downcomers. In such a case of course these water tubes must open into the drum 2 below water level.

The assembling of the evaporator can take 5 place as follows:

The top and bottom plates provided with the necessary holes for the water tubes are put over the water tubes not yet bent and provisionally fixed at half height of the tubes, the ends of 10 which thereupon are curved inward and finally fixed into the drums 2 and 3 by a welding or rolling process. The top and bottom plates 8 and 9 are then brought into their correct position, the tubes are welded on at the points where they 15 perforate the plates, and after that the top and bottom plates and the walls 4, 7, 10 and 11 of the jacket are welded together or joined by riveting. The inner wall 7 consists of different sections which are inserted in the interior through 20 the slot A between the walls 10 and 11, and thereupon welded or riveted to form the cylindrical wall 7 of the jacket.

As compared with the usual methods of constructing such evaporators, the new construction 25 described herein possesses the following advantages: Should the rolled or welded points of junction 6 of the water tubes commence to leak the steam or water seeping through will become noticeable at once, and the points of leakage can be 30 made tight without delay. Neither water nor steam can come in contact with the heating liquid because the heating jacket is arranged in such a manner that it does not encase the points of junction 6. This is an important advantage, 35 as the steam would be liable to disintegrate the heating fluid, especially as the temperature occurring in practice ranges at 660° F. and higher and together with the heating fluid would corrode the iron parts. This would happen with 40 oils having a high boiling point, as well as with fusions of salts. The same advantage will be realized at points 12 where the water tubes perforate the top and bottom plates 8 and 9 of the heating jacket. In case of leakages occurring 45 at these points no water or steam can enter the heating jacket, even if some of the heating fluid should seep out.

Above all the new design offers a possibility of repairing leakages at the points of perforation by 50 re-welding or re-caulking, or by re-packing and tightening the stuffing boxes, should the tubes be provided with such stuffing boxes. All previous constructions lacked this possibility because the points where the water tubes perforate the heating jacket, are too close together to permit repairs. In our constructions as described hereinabove, the boiler tubes are arranged as two concentric circles having such a diameter that all 55 the water tubes of an evaporator can be accommodated. Consequently it becomes possible to subject all perforations 12 to a careful control and continual supervision, and the perforations are well accessible from all directions and can be therefore worked upon for repairs with the necessary tools.

The opening A forming a slot along the heating jacket is not only important for the purpose of an easy assemblage of the inner wall 7, but it also makes it possible to compensate tension strains 60 existing in the casings of the jacket, which strains are due to possible differences of temperature. Tensions between the jacket and water tubes on the one hand, and the drums connected with each other by the downcomer on the other hand, 65 are absorbed by the curve ends of the water tubes.

If necessary, the downcomer can be provided with a compensation neck such as the neck 26 shown on Fig. 5.

In the illustrations 3 and 4 another model of the evaporator is demonstrated. The corresponding parts of the evaporator are indicated by the same indexes as in Figs. 1 and 2. The water tubes 1 are arranged vertically and have curved ends. They open into the horizontal drums 2 and 3 and are welded on at the points 6, or rolled in. The 10 tubes are grouped as 4 sections having two rows each. Each group of pipes is encased in a box-like heating jacket consisting of the side walls 4 and 7, the top and bottom plates 8 and 9, and the frontal plates 10 and 11. The side plates 4 15 and 7 run parallel to the axes of the drums. The height of the boxes corresponds to the length of the heating tubes, their width to the length of the drums 2 and 3, and their depth is somewhat wider than the sum of the distance between 20 the two rows of tubes and their diameters. The points where the heating jacket is perforated by the water tubes, are marked 12. Everyone of the above mentioned four boxes has a flanged socket 13, and another socket 14 for the heating liquid 25 at the other end of the box which is not illustrated. The steam is conveyed from the upper drum through the socket piece 15, the feed water is supplied through socket piece 16 of the lower drum. Upper and lower drums are connected 30 by several downcomers 5.

The advantage of the invention is particularly evident in this manner of construction. If all tubes would lead from drum 2 to the lower drum within a single boxlike heating jacket and with 35 all tubes lying close together as rows, a control of the rolled joints 6 and the points of perforation 12 would perhaps be possible, but a repair of the points of perforation would be impossible, if a leakage should occur. In the new construction 40 within each jacket not more than two rows of tubes are arranged. These jackets are at such a distance from each other that the points of perforation 12 of the water tubes into the heating jacket are quite accessible and repair work can 45 be carried out at any time.

The assembly of the evaporator can take place in the same manner as already described in the first model of construction as shown in Figs. 1 and 2. Here also one would first of all slide the top 50 and bottom plates over the as yet straight water tubes. The water tubes would thereupon be curved at their ends and then be fitted to the drums by a rolling or welding process. Now the top and bottom plates 8 and 9 are put into their 55 correct position and the side walls 4, 7, 10 and 11 are joined to them by welding or riveting.

A third model is illustrated by Figs. 5, 6, 7 and 8.

The water tubes 1 are in this construction placed closely together forming a bundle of tubes 60 encased by the cylindrical part 4 to which on the top and bottom conical parts 11 are attached, and upon which subsequently the cylindrical parts 18 having a considerably larger diameter than the part 4 are fixed. The parts 4, 17 and 18 form the 65 heating jacket together with the top and bottom plates 8 and 9. The different parts 4, 17, 18, 8 and 9 of the heating jacket are either welded or riveted together, or they are joined by flanges, as shown in our drawings. The water tubes 1 are 70 bent outwards at their ends and emerge from the heating jacket through the cylindrical part 18 on different planes arranged one above the other. There are so many different planes that on each 75 level only a restricted number of water tubes

emerge from the jacket. On the other hand the diameter of the cylindrical section 18 is so large that each of these perforations 12 is so far distant from the next, that everyone of them is easily accessible from all sides. The perforations in each plane can be arranged vertically one below the other forming several groups, the perforations of each group being situated always on two closely neighboured generatrices of the cylinder 18. In the drawings they are alternating chevronwise from right to left forming several groups of two closely neighboured generatrices of the cylinder 18.

The number of planes can of course be varied, and a smaller or greater number can be used. Of course then the diameter of the cylindrical part 18 must be chosen in accordance smaller or larger, in order that the distances of the perforation points be the same as before. The tubes leaving the jacket enter at 6 small chambers, 2 and 3, four of which are arranged on top, and four below. From the chambers 2 downcomers 5 lead to the lower chambers 3. It is, however, advisable that the downcomers do not lead to that chamber which is situated vertically below the upper chamber in question, but to a neighbouring one, whereby the downcomer 5 is provided with two curved parts serving as compensating necks. The steam from the several chambers 2, together with such water as has not separated out and passed into the downcomers 5, is injected through the pipe-lines 19 to the steam drum 20. The steam is then delivered by the socket 21. The deposited water flows through pipe 22 into a small collecting vessel 23 into which the feed water flows through the pipe 24. The water is supplied to the water tubes 1 through the pipe-lines 25 which connect the drum 23 with the lower chambers 3. The heating fluid enters the heating jacket through the socket 13, and leaves it through the socket 14 or vice versa. The heating jacket is provided with a compensation rib 26 which serves to compensate tensions and stresses due to heat differences existing between the heating jacket and the water tubes.

The mounting of the evaporator can take place so that part 4 and the conical parts 17 of the heating jacket are slipped over the water tubes prior to the latter being curved. The cylindrical part 18 is made of separate parts welded or riveted to each other and with the water tubes. Inside of the heating jacket, the water tubes can be kept in their correct position by suitable means.

This model of construction is superior to other constructions by its particularly low rate of flow resistance regarding the heating fluid within the heating jacket. Another advantage is that all of the water tubes are arranged closely together, the cubic contents of the heating jacket consequently being very low and the required quantity of heating fluid thereby remaining small. Nevertheless the advantageous features of other models have been also maintained in this our construction. The joints 6 between the water tubes and the collecting vessels and the points 12 where the water tubes pass through the heating jacket are arranged so that in case of leakages occurring, water or steam cannot seep into the heating fluid. Furthermore the points 12 where the water tubes perforate the heating jacket, are at such a distance from each other that all tubes are accessible near the points of perforation and can be repaired from every direction.

Without altering the nature of this invention it is also possible to put into practice other models of the invention. For instance in the model illus-

trated in Figs. 5, 6, 7 and 8 the water tubes can be passed through the top and bottom plates 8 and 9 of the heating jacket. In this case, however, it would be advisable to arrange the points where the water tubes pass through the heating jacket so that they form pairs of concentric circles which alternatingly are close together or far distant from each other. Annular collecting chambers would then replace the different small collecting chambers 2 and 3, one annular chamber 10 to be arranged above and one below each heating jacket.

Furthermore as an alternative in the model shown in the Figs. 3 and 4 the box-shaped heating jackets can also be arranged at a 90° angle to the axis of the drum, and not parallel to this axis, as is illustrated in Figs. 3 and 4.

It is thus clear that our invention may be embodied in other specific forms than those herein disclosed without departing from our invention, and we therefore desire the described embodiments to be considered in all respects as illustrative and not restrictive.

We claim:

1. An indirectly heated evaporator comprising a liquid tight jacket, means for supplying and withdrawing heating fluid from said jacket, a multiplicity of water tubes arranged in a plurality of continuous rows extending within said jacket and through a wall thereof, a collector spaced from said jacket and into which said water tubes lead, said water-tubes having their multiplicity of points of passage through said jacket wall disposed so as to render all said points of passage through said jacket wall readily accessible from practically all directions.

2. An indirectly heated evaporator according to claim 1, the said disposition of the multiplicity of points of passage of said multiplicity of water-tubes through said jacket being arranged in rows, and said rows being arranged in one or more groups with but a small number, as two, rows to the group, and the structure providing access to said group or groups at both sides thereof.

3. An indirectly heated evaporator according to claim 1, the said disposition of the points of passage of said water-tubes through said jacket being in two rows, i. e. paired rows, with the tubes of the respective rows in alternating chevronwise arrangement, substantially as described.

4. An indirectly heated steam generator or the like, of the type comprising upper and lower collector drums, upcomer tubes surrounded by a heating jacket and at least one downcomer tube; constructed with said upcomer tubes arranged in a plurality of continuous adjacent rows passing through the wall of said jacket and traversing a space before passing into the collector drums, so that leakage at either set of points of passing will not result in leakage of heated fluid into heating fluid or vice versa, and said upcomer tubes being arranged at at least one of said sets of points of passing so as to render all points of passing of said set readily accessible from practically all directions.

5. A heat exchanger of the class described, comprising a jacket having a portion of relatively small cross-section intermediate its end portions and having its end portions enlarged to a relatively greater size, a multiplicity of tubes extending through said jacket and projecting through the walls of its enlarged end portions, those portions of said tubes lying within the intermediate portion of said jacket being arranged in relatively closely spaced relation, and those portions of the

tubes extending through the walls of the enlarged end portions being more widely spaced, thereby facilitating maintenance of tight joints between the tubes and jacket walls, said relatively small intermediate section of said jacket and the close arrangement of the tubes therein restricting the volumetric capacity of said jacket, and means for supplying and withdrawing fluid from said jacket.

6. A heat exchanger according to claim 5, said tubes extending through and beyond the walls of said jacket in rows, and said rows being arranged in a plurality of groups with but a small number, as two, rows to the group, and the structure of said heat exchanger providing access to said groups at both sides thereof.

7. A heat exchanger according to claim 5, said tubes extending through and beyond the walls of said jacket in two rows, i. e. paired rows, with the tubes of the respective rows in alternating chevronwise arrangement, and the structure of said heat exchanger providing access to said paired rows at both sides thereof.

8. An evaporator according to claim 1, said heating jacket having a relatively large portion and a relatively small portion, said tubes lying closely adjacent one another within said relatively small portion, said tubes passing through the wall of the relatively large portion, said enlargement providing for separation of the tubes before their passage through said wall and thereby providing for their disposition as aforesaid.

9. An evaporator according to claim 1, said jacket having a central portion and widened end portions, said tubes extending through said central portion closely adjacent one another, and said tubes bending within said widened end portions and extending through said jacket wall at points laterally of said widened end portions with the points of passage thereof disposed as aforesaid.
